UNITED STATES PATENT OFFICE.

MARY V. CONNER, OF TUSKEGEE, ALABAMA.

DESIGN FOR AN ASH-PAN.

SPECIFICATION forming part of Design No. 26,686, dated February 23, 1897.

Application filed January 16, 1897. Serial No. 619,485. Term of patent 14 years.

To all whom it may concern:

Be it known that I, MARY VIRGINIA CONNER, a citizen of the United States, residing at Tuskegee, in the county of Macon and State of Alabama, have invented and produced a new and original Design for an Ash-Pan, of which the following is a specification, reference being had to the accompanying drawings, forming a part thereof, in which—

Figure 1 is a perspective view of an ash-pan embodying the features of my design, and Fig. 2 is a bottom plan view of the same.

The object of the design is not only to provide a pleasing and graceful contour for the pan, but also to so shape the said pan that it will conform to the general lower outline of the basket of the grate and the surface of the hearth beneath the grate.

One of the features of the design consists in a back A, of greater height than the front

B, and sides C, connecting the front and back. The upper edges of the sides, commencing at the upper edge of the back, are given a convex contour, while the forward upper portions of the said side edges meet the upper edge of 25 the low front B.

Another feature of the design consists in a handle D, of skeleton formation, placed at the front of the pan, and the continuation of the side members of the handle along the bottom 30 E of the pan, one in direction of each rear corner, forming diagonal ribs F.

I claim—

The design for an ash-pan herein shown and described.

MARY V. CONNER.
